UNITED STATES PATENT OFFICE.

JOHN CLEMENT HUGHES, OF NEW YORK, N. Y.

ATTACHMENT FOR PENS.

1,143,629.

Specification of Letters Patent.

Patented June 22, 1915.

Application filed November 20, 1912. Serial No. 732,529.

To all whom it may concern:

Be it known that I, JOHN CLEMENT HUGHES, a citizen of the United States of America, residing in the borough of Manhattan, city and State of New York, have invented a new and useful Attachment for Pens; and I do hereby declare the following to be a full, clear, and exact description of the same.

10 This invention relates to improvements in caps for pens, penholders and similar articles. For this purpose, I have provided a cap, such as the usual fountain pen cap, in the upper part of which I provide two reservoirs for the eradicator, such reservoirs having improved closers at their tops, and from which closers depend two spreaders by which the eradicator is applied when desired. A suitable screw cap is provided to fit over the closers to keep the same liquid tight.

20 Other details and objects will suggest themselves as the description proceeds, and I do not limit myself to the uses and details 25 specially mentioned, since various changes may be made without departing from the spirit and scope of the invention as claimed.

Referring now more particularly to the drawings:—Figure 1 is a side elevation of 30 the pencap shown applied to a fountain pen or other device; Fig. 2 is an axial sectional view of the device; Fig. 3 is a transverse sectional view taken on the line 5—5 of Fig. 2.

35 Referring more particularly to Fig. 1, it will be seen that the cap-body 10 is fitted upon the fountain pen or other device 11 in the usual way and is provided itself with a small terminal cap 12.

40 The cap-body 10 is adapted for ink eradicator which require two separate liquids, and here two upper bores or receptacles 15 and 16 are provided, each of which is provided with separate covers 20 and 21 having 45 inserted therein the spreaders 24 and 25 respectively.

The top part of the pen-cap 10 is provided with external screw-threads for engagement with the internally threaded screw-cap 12. Upon placing the threaded screw-cap 12 50 in engagement with the threaded part of the pen-cap 10 and tightening the same, this screw-cap forces the closers 20 and 21 into liquid tight engagement with the tops of the receptacles 15 and 16. 55

In the device, the terminal cap is removed and the liquids used one after the other by taking hold of the covers 20 or 21 as a handle and rubbing the spreader on the paper.

I claim:

1. A pen cap comprising, a tubular body having a pair of upper receptacles of substantially semi-circular cross-section and a single partition therebetween; a pair of flanged covers received in the upper ends 65 of the receptacles respectively; a spreader depending from each cover; and a cap having threaded engagement with said body and pressing the top of said covers and forcing the flanges into tight engagement 70 with the top of the receptacles. 60

2. A device of the character described, comprising a tubular body having a pair of upper receptacles of substantially semi-circular cross-section and a single partition 75 therebetween; a pair of flanged covers received in the upper ends of the receptacles respectively; a spreader depending from each cover; a means engaging with said body and pressing the top of said covers 80 and forcing the flanges into tight engagement with the top of the receptacles. 70

In testimony whereof, I have signed my name to this specification in the presence of two subscribing witnesses.

JOHN CLEMENT HUGHES.
